2 Claims. (Cl. 257—256)

The present invention relates to a heat exchanger of the type having a tube secured to an elongated heat conductive member by deformation of the member.

In conventional plate and tube type heat exchangers, an elongated sinuous tube is generally secured to a backing plate of high thermal conductivity by brazing, soldering or welding. It has heretofore been proposed that the tube be secured in this manner within a shallow depression formed in the plate so that the heat transfer efficiency of the exchanger may be increased. Due to the necessary provision of means, such as welding or brazing, to secure the tube to the backing plate, such heat exchangers have been expensive and complicated in manufacture and the efficiency of heat transfer from the tubes to the plate has been low due to the necessarily small area of contact therebetween.

One form of the present invention comprises an improved type of tube and plate heat exchanger similar to that disclosed in my copending application Serial No. 36,598 filed July 2, 1948 now Patent No. 2,585,043 granted February 12, 1952, and assigned to the assignee of the instant application, in which the tube is firmly secured to the plate without the employment of external securing means, such as welding or brazing, and in which the area of contact between the tube and the plate is greatly increased to insure efficient heat exchange. In general, the heat exchanger of the present invention comprises an elongated heat conductive member and a tube secured to the member by deformation of the member into more than semi-peripheral contact with the tube.

The present application is a continuation-in-part of Serial No. 332,693, filed January 22, 1953 now Patent No. 2,732,615 granted January 31, 1956, which in turn was a continuation of Serial No. 80,240 filed March 8, 1949 and Serial No. 124,179 filed October 28, 1949, Serial Nos. 80,240 and 124,179 now being abandoned.

The securing of the tube to the plate, as carried out by one embodiment of the method of the present invention, involves the forming of a groove or depression in the plate, the placing of a tube in the groove, the tube having a diameter less than the depth of the groove, and the formation of additional depressions or grooves in the plate by deforming portions of the plate immediately contiguous to the first formed depression. In this manner, the plate is deformed into greater than semi-peripheral surface contact with the tube to overlie a median diameter of the tube, thus anchoring the tube to the plate with the relatively great surface contact therebetween insuring efficient heat transfer from the tube to the associated backing plate.

This method is satisfactory for use in the formation of heat exchangers employing tubes having relatively small outside diameters, e.g., on the order of one quarter inch or less, and it may also be used with larger diameter tubes if desired. However, it has been found that in the use of the method with tubes of outside diameters on the order of from $\frac{3}{8}$ to $\frac{1}{2}$ inch or larger, the tube often does not have sufficient structural resistance to re-

tain its original circular cross-sectional shape without permanent distortion of the tube where the metal plate is folded or swaged back on the tube into interlocking engagement therewith. This deformation of the tube may prevent close gripping peripheral contact between the tube and the plate along the entire length of the tube and thus may seriously interfere with the heat transfer efficiency of the heat exchanger.

Of course, the tube wall thickness may be increased to prevent such tube distortion, but this is not economically feasible due to the increased cost of such tubing. Further, tubing of relatively thin wall thicknesses, while of insufficient strength to resist distortion during forming of the exchanger, has sufficient bursting strength and other structural characteristics for the actual operational demands imposed upon it in use, and also thin-walled tubing is desirable for reasons of heat transfer efficiency.

A further embodiment of the present invention now makes possible the employment of tubing of relatively large diameters and relatively thin wall thicknesses in the formation of plate and tube type heat exchangers by a method generally similar to that above outlined. This further embodiment contemplates the positioning of the tube within a groove formed in a backing plate of desired thermal conductivity, the distortion or swaging of the groove side walls and the plate portions immediately adjacent thereto into engagement with the tube, and the distortion of the tube radially outwardly into closely gripping engagement with the swaged portions of the plate to insure a snug fit between the plate and the tube and the efficient transfer of heat between the tube and the plate.

The heat exchanger of this further embodiment thus comprises generally a backing plate of high thermal conductivity and a tube in interlocked engagement with the plate, both the tube and the plate being deformed from their configuration prior to assembly into tightly gripping, interlocked, thermally efficient engagement.

In accordance with still another embodiment of the present invention, a tube and wire heat exchanger is manufactured by forming wires about more than a semi-periphery of each of a series of tubes. Tube and wire heat exchangers at the present time involve a large number of welds per assembly, for example as many as 2600, and fabrication of such assemblies involves extremely expensive and complicated machinery. Further, if the tube is burnt through in the welding operation at even a single one of the 2600 welds, the entire assembly must be discarded. By eliminating the welding as a fastening means, the costly equipment and danger of weld failure is avoided and important savings are effected.

It is therefore an important object of the present invention to provide an improved type heat exchanger in which a tube is secured to a heat conductive member without the employment of external fastening means.

Another object of the present invention is to provide an improved method of making a heat exchanger by deforming a heat conductive member into greater than semi-peripheral surface contact with the heat exchange tubing to maintain the components in assembled efficient heat transfer relation.

It is a further important object of the present invention to provide a heat exchanger in which heat exchange tubing is secured within a groove or bend formed in a heat conductive member, with portions of the member extending into conforming contact with the tube above a median diameter thereof to securely lock the tube to the member.

A still further important object of this invention is to provide an improved method of forming a heat exchanger having a heat conductive member and heat exchange tubing.

Still another object of the present invention is to provide a method of making a heat exchanger by disposing a tube in a groove or bend formed in a heat conductive member and depressing immediately contiguous portions of the member to force the member into greater than semi-peripheral contact with the tube.

It is an additional important object of the present invention to provide an improved method for the manufacture of plate and tube type heat exchangers, in which the tubes of the heat exchanger are of relatively large diameter and of relatively thin wall thickness.

Another important additional object of the present invention is to provide an improved plate and tube type heat exchanger including a backing plate in tightly gripping engagement with a tube deformed radially outwardly into engagement with the plate.

Still another important additional object of the present invention is to provide an improved method of making a tube and plate type heat exchanger including the steps of positioning a tube in a groove formed in a backing plate, swaging adjacent portions of the plate into engagement with the tube to overlie a median diameter thereof, and deforming the tube radially outwardly into snug fitting, interlocking engagement with swaged portions of the plate.

A further more specific object of the present invention is to provide an improved tube and wire type heat exchanger.

Other and further important objects of the present invention will be apparent from the disclosure in the specification and in the accompanying drawings.

Figure 20 illustrates a sinuous wire configuration for providing a plurality of parallel lengths on which the method of Figures 15 to 19 may be practiced.

As shown on the drawings:

In Figure 1, reference numeral 10 refers generally to a heat exchanger of the plate and tube type including a backing plate 11 and a continuous length of tubing 12 of sinuous shape secured to the backing plate 11. It is to be noted that those portions of the serpentine or sinuous length of tubing 12 extending across the width of backing plate 11 are substantially straight while the connecting curved portions of the tubing 12 extend beyond the backing plate 11. In this manner, it is not necessary to deform the backing plate 11 into a serpentine or sinuous path to receive the tube 12 but rather, it is only necessary to secure the straight portions of the tubing 12 to the backing plate 11.

The method of securing the serpentine or sinuous length of tubing 12 to the plate 11 as herein described insures the efficient transfer of heat from the tubing 12 to the relatively large heat transfer surface of plate 11.

The plate 11 is initially deformed to provide a plurality of parallel, spaced depressions or grooves 13 to receive each of the substantially straight portions of the tubing 12. Each of the depressions or grooves 13, as best shown in Figure 2, is provided with a closed arcuate bottom 14 and upstanding side walls 15 extending upwardly from the closed bottom 14. The depth of groove 13 is preferably greater than the external diameter of the tubing 12 for reasons which will be hereinafter more fully described.

After the grooves have been formed in the plate, each side of the plate is placed in turn between the trimming and forming dies 25 and 26. The lower die 26 is provided with a pair of elongated grooves 27 receiving the grooved portions 13 of the plate adjacent a side edge thereof so as to accurately index the plate in the die. An edge portion indicated at 28 of the plate is then removed by means of a shear blade 29. It will be observed that simultaneous with the trimming operation, the side edge portion 11a of the plate is displaced downwardly by means of cooperating portions 25a and 26a of the dies. A portion 11b of the side edge 11a may be formed to slope at an angle of approximately 30° to the major plane of the plate and to join with the groove upstanding side wall 15 on a $\frac{3}{16}$ inch radius bend 11c. The purpose of offset portions such as 11a at the side edges of the plate is to insure proper action of the forming dies of Figures 3 and 4 in wrapping the plate about the tube length in the laterally outermost groove in the plate as will hereinafter be more fully discussed.

As the next step of the method, the tubing 12 is positioned within the grooves or depressions 13. In the manufacture of a heat exchanger such as that illustrated in Figure 1, only the straight portions of the serpentine tubing are placed within the grooves 13 with the curved portions of the tubing extending beyond the plate 11. It is to be noted that when the tube 12 is bottomed within the depression or groove 13, peripheral contact between tube and groove is established, the outer periphery of the tube having approximately the same radius of curvature as the inner periphery of the arcuate groove bottom 14, so that the tube 12 fits snugly within the groove 13.

The securing of the tube within the plate depressions 13 is carried out by a pair of cooperating dies 16 and 17.

The dies 16 and 17 are preferably of such size as to receive the entire exchanger unit 10 shown in Figure 1. The backing die 16 is recessed as at 18 to provide support for the bottom 14 of the groove 13. The backing die 16 is also recessed, as at 19, immediately adjacent each side of the recess 18. The recess 19 is preferably contiguous with the entire length of the recess 18 and with the width of the backing plate 11.

A movable forming die 17, adapted for cooperation with the backing die 16, is provided with a pair of arcuate protuberances 20 separated by an arcuate depression or groove 21. As shown in Figure 4, one of the protuberances 20 is adapted to extend into each of the grooves 19 of backing die 16 and arcuate recess 21 is adapted to receive the tubing 12 as the upper die 17 completes its work stroke.

Figure 3 indicates the position of the dies 16 and 17 prior to forming the plate about the straight lengths of tubing 12. As the die 17 moves downwardly, the protuberances 20 engage the plate laterally outwardly of bends 11d formed between the plate lands L and the upstanding side walls 15 of the grooves. Further downward movement of the upper die 17 results in a deflection of the land portions L as indicated by the dash lines so that a central portion of each land L is bottomed against the surface 16a of the lower die 16. It has been found to be very important to limit the downward deflection of the lands L of the plate in the manner illustrated in Figure 3 in order to obtain the uniform and symmetrical wrapping of the plate about the tube on both sides of the tube as indicated in Figure 4. In one embodiment, the bottoming of the deflected portions of the lands L occurred in the first .020 to .030 inch of downward travel of the upper die from the position indicated in Figure 3. It is believed that the bottoming of the lands L as shown in dash outline in Figure 3 serves to prevent the bends 11d between the groove side walls and the lands from moving laterally outwardly out of proper engagement with the respective protuberances 20. In the deflected condition of the lands L shown in dash outline in Figure 3, the protuberances 20 progressively lock around the bends 11d between the lands L and groove side walls. In one embodiment, the protuberances 20 were found to be locked about the bends 11d between the lands and the groove side walls after a total punch travel of approximately .050 to .060 inch.

The upper die 17 causes the lands to lie flat against the lower die surfaces 16a and the side walls to be formed around the tube substantially as in the final product after a total downward travel of the upper die 17 of approximately .100 to .110 inch, this stage in the operation being completed before the upper die 17 reaches bottom or the limit of its total travel.

The dies are designed so as to travel a further and final $\frac{1}{32}$ of an inch downwardly, and this final movement stretches the metal of the lands and swages the metal around the tubes, placing this metal under compression so that it will not spring away from the tube after removal from the die. In fact it has been found that the plate is actually under a tensile stress at the portions thereof wrapping the tube after removal from the forming dies. This is indicated by constriction of the portion of plate wrapping the tube if the tube is removed therefrom. The plate land portions remain flat and in substantially a single plane with an apparent stiffness after removal of the assembly from the dies as a result of this swaging operation and stretching of metal between the grooves. In the illustrated embodiment, the tube may have a $\frac{1}{4}$ inch outside diameter and a wall thickness of about .028 inch while the plate may be of 22 gauge steel having a thickness of about .030 inch.

The dies shown in Figure 4 show the exact proportions of the protuberances 20 and recesses 19 in relation to the tube diameter for the embodiment illustrated.

The edge portion 11a of the plate adjacent the outermost groove is offset in such a manner as to bottom against the portion 16a of the lower die 16 to tend to resist lateral outward displacement of the bend portion 11c and thus to promote locking of a corresponding protuberance 20 about the bend 11c in the plate between the sloping plate portion 11b and the groove side wall portion 15. Further the formation of the sloping portion 11b adjacent the bend 11c provides a shoulder facing laterally outwardly against which the associated protuberance 20 of the upper die may engage as the die 17 moves downwardly to prevent laterally outward movement of the edge portion 11a which is not constrained between a pair of plate groove portions as are the land portions L of the plate.

It may be noted that the portions 17a of the upper die can be still further recessed as indicated in dotted outline at 17b in Figure 4 so as to avoid contact between the upper die and the land portions L of the plate without adversely affecting the final product. No compression of the land portion L by the upper die is necessary to the rigid planar plate configuration achieved by the method of Figures 1 to 4.

The land portions L of the plate may be uniformly 25 perforated with circular holes or made of integral expanded metal portions over the entire area thereof with the plate having imperforate solidly continuous main and auxiliary groove portions, as disclosed in my co-pending application Serial No. 88,342. In Figure 5, holes 30 such as shown at 9 would be uniformly distributed along the planar portions of the plate 31.

It will be understood from the drawings that the sloping die faces such as 20a in Figure 4 engage with portions of the plate laterally outwardly of the bends 35 22a in Figure 4 and force said plate portions inwardly by a wedging action as the upper die descends. The lower faces 20b of the protuberances cause what may be termed a "peeling" action as they move downwardly, that is, the metal of the plate forms a bend at 40 successively lower portions of the side wall 15 as the upper die descends, until the bend has shifted from the position shown at 11d in Figure 3 to the position indicated at 22a in Figure 4. As a result of the converging configuration of die faces 20a, portions of 45 the plate are formed inwardly into overlapping relation to the tube 12 without any need for holding the edges of the plate against laterally outward movement.

As will be apparent from Figure 4, the protuberances 20 in the preferred embodiment cause acute angle folds 50 of metal 22 to be formed at each side of the tube at the junction between the main groove 13 and adjacent auxiliary grooves 23 and 24, respectively. The opposed pairs of such metal folds 22 overlie each tube length 12 and lock the tube length in the main groove. The forces 55 employed in reshaping the metal of the plate around the tube 12 are of such magnitude as to cause the plate material 11 to conform to the tube in spite of any commercial variations in the tube diameter or any lack of roundness of the tube, thereby insuring a consistent metal-to-metal contact between the tube and the plate at all 60 times. Further, the portion of the plate wrapping the tube is preferably under a tensile stress which tends to cause the plate to tightly and positively grip the tube with a resiliently tensioned gripping force to insure optimum heat transfer contact between the tube and plate.

By way of example, a pressure of the order of 2 to 3 tons per lineal inch on an assembly having a $\frac{1}{4}$ inch O.D. tube with a wall thickness of .028 inch and a plate of .030 inch thickness was required to set the metal so that upon release of such pressure and removal of the panel assembly from the die, the panel as a whole remained in a relatively flat condition.

The method of the present invention thus includes the steps of rigidly and conformingly backing the plate groove portions 14 by means of die grooves 18 and also

backing the plate land portions L by means of die surface $16a$, while leaving effectively unbacked the upstanding groove wall portions, the bends $11d$, and contiguous portions $11e$ of the plate. The unbacked portions are then reshaped to form folds 22 and to move the folds inwardly into conforming relation to the tube 12 .

It may thus be seen that the backing plate 11 is deformed into greater than semi-peripheral contact with the tube 12 . Both side walls 15 of each groove 13 are thus deformed inwardly into contact with the outer periphery of the tube to overlie a median diameter of the tube and effectively prevent its removal from its position within the recess 13 . It will be understood that the supplemental grooves 23 and 24 may be coextensive with the main groove 13 , or that supplemental grooves may be formed only at spaced points along the length of the main groove.

The heat exchanger, as shown in Figure 1, thus includes the backing plate 11 and the continuous, sinuous tube 12 , the straight portions of which are secured within recesses or grooves formed in the backing plate 11 by deformation of the backing plate into greater than semi-peripheral contact with the tubing. The immediately contiguous main groove 13 and the supplemental grooves 23 and 24 lie on the same side of the plate 11 , with the metal of the main groove in contact with the tube to securely lock the tube in the groove. It has been found that this relatively great surface contacting area between the backing surface and the tube increases the efficiency of heat transfer over those welded tube and plate type heat exchangers of the prior art.

In Figure 5, reference numeral 30 refers generally to the heat exchanger of the plate and tube type including a backing plate 31 and a continuous length of tubing 32 of sinuous shape secured to the backing plate 31 .

It is to be noted that those portions $32a$ of the serpentine or sinuous length of tubing 32 extending across the length of the backing plate 31 are substantially straight with the connecting curved portions $32b$ of the tubing 32 extending beyond the backing plate 31 . In this manner, it is not necessary to deform the backing plate 31 into a serpentine or sinuous path to receive the tube 32 , but rather it is only necessary to secure the straight portions of the tube to the backing plate.

The method of securing the serpentine length of tubing to the plate 31 , as herein described, insures the efficient transfer of heat from the tube 32 to the relatively large heat transfer surface of the plate 31 . The plate 31 may be any desired sheet metal having a high heat transfer efficiency and suitably may be a mild, low carbon steel having a thickness on the order of No. 20 U.S.S. gauge (0.0359 inch), and the tube is preferably formed of copper of an outside diameter on the order of $\frac{3}{8}$ to $\frac{1}{2}$ inch and a wall thickness of about 0.0359 inch. Other metals than copper, such as iron or steel, or aluminum, may be used for the tube, and larger diameters than indicated may be employed in the method of my invention. The tube is suitably seamless but may be a welded tube.

The plate 31 is sufficiently deformed to provide a plurality of parallel, spaced depressions or main grooves 33 each extending across the length of the plate for receiving each of the substantially straight portions of the tube 32 . The grooves 33 may desirably be formed as illustrated in Figure 6 by the cooperation of a pair of rolls 34 and 35 . The roll 34 is provided with a central, radially outwardly extending annular embossment 36 , while the roll 35 is provided with a peripheral annular groove 37 for receiving the embossment 36 and that portion of the plate 31 confined between the rolls. It will be seen that when the plate 31 is passed between the rolls 34 and 35 that the groove 33 is formed therein to extend thereacross. Dies may be used in place of the rolls 34 and 35 .

Each of the grooves 33 is provided with an arcuate bottom portion 38 and parallel upstanding straight side

walls $38a$. The depth of the groove 38 is greater than the exterior diameter of the tubing 32 and determines the amount of wrap of the metal of the plate about the tube. As will hereinafter become more apparent, the greater the depth of the groove, the greater the amount of wrap about the periphery of the tube. It will be noted from Figure 7 that when the tube 32 is positioned within the groove 33 , the tube and the arcuate groove bottom 38 are in close fitting peripheral contact, since the arcuate groove bottom 38 has approximately the same radius of curvature as the outer periphery of the tube. It will be understood that in the manufacture of a heat exchanger such as that shown in Figure 5, only the straight portions $32a$ of the tube 32 are bottomed within the grooves 33 and that the curved portions $32b$ of the tube 32 extend outwardly beyond the lateral edges of the plate 31 .

In the next step in the method of making the heat exchanger, the straight lengths of the tube are interlocked within the grooves 33 by means of a pair of cooperating dies 39 and 40 . The dies 39 and 40 are preferably of such size as to receive the entire exchanger unit 30 shown in Figure 4. The backing die 39 is recessed as at 41 to provide a conforming support for the bottom 38 of the groove 33 . The backing die 39 is also recessed, as at 42 , immediately adjacent both lateral edges of the groove 38 , the recesses 42 being preferably contiguous with the entire length of the recess 41 , i.e. with the full length of the backing plate 31 .

The second forming die 40 is adapted for movement relative to the backing die into and out of cooperating relationship with the backing die 39 . The movable die 40 is provided with a pair of spaced parallel, arcuate protuberances 43 separated by an arcuate depression or groove 44 (Figure 7). The groove 44 is provided with an elongated, generally rectangular recess 45 in which is secured an elongated insert punch bar 46 of rectangular cross-section having a depending flat face 47 .

As shown in Figure 7, the protuberances 43 serve to deform the metal of the backing plate 31 into the cooperating grooves 42 . However, even after full closing of the dies 39 and 40 , as shown in Figure 8, no contact is made between the portions of the plate contiguous to the groove 38 and the bottoms of the grooves 42 . This is because the protuberances 43 are shallower than the grooves 42 .

The metal immediately acted upon by the protuberances 43 , as the upper die 40 is moved toward the lower die 39 , is that of the unbacked portions $31a$ of the plate laterally contiguous to the also unbacked upstanding wall portions $38a$ of the groove 33 . The laterally contiguous portions $31a$ are first deflected downwardly into a configuration similar to that shown in dotted outline in Figure 3. Thereafter, as the dies 40 and 39 continue to move relatively toward each other, the metal of the unbacked portions $31a$ is moved inwardly about the tube as a mandrel to form nearly closed folds 48 extending into the clearance on either side of the punch bar 46 . The inwardly deformed folds 48 are caused to lap the adjacent tube wall and to wrap more or less of the upper periphery of the tube depending upon the original depth of the groove 33 . The result is that the metal of the plate wraps more than a half of the periphery of the tube and thus locks the tube in its groove 33 .

By the coaction of the forming dies, the plate 31 is provided with a pair of parallel shallow supplementary grooves 49 laterally contiguous to and coextensive with each main groove 33 .

Also, in the latter stages of the closing movement of the cooperating dies 39 and 40 , the lower face 47 of the insert 46 contacts the exposed surface of the tube 32 between the folds 48 to deform such surface inwardly and at the same time expands the rest of the tube radially outwardly into tight gripping, interlocked engagement with the inner surfaces of the groove 33 and of the deformed portions 48 of the plate 31 . The forming dies 39 and 40

are moved together under relatively heavy forces of such magnitude as to deform both the plate and the tube into interlocking engagement to insure at all times an extended metal-to-metal surface contact between the tube 32 and the plate 31.

As previously indicated, the extent to which the metal of the plate is wrapped about the tube can be varied by varying the depth of the groove 33. Regardless, however, of the extent of the wrap of plate metal about the tube, it is preferable, for a given depth of the groove 33, to so arrange and dimension the profiles of the cooperating dies 39 and 40 as to effect a cold working of the metal that is deformed by the dies. Such cold working is effected not only by the deformation of the metal but by an actual stretching of the metal due to the fact that there is not initially at the stage of the operation illustrated in Figure 7 a sufficient length of unsupported metal to form the supplemental grooves 49 and the folds 48 and to lap said folds about the tube. In addition, there is a slight stretching of the metal in the lands L between adjacent grooves 38 due to the action of protuberances 43, which stretching occurs during the final closing movement of the dies 39 and 40. The lands are not tightly clamped between the flat die faces even after the deformation of the unsupported metal has occurred.

Thus, as a result of the cold working of the metal during the swaging or deforming operations, and the pressure subsequently applied, the metal takes a permanent set under a tension tending to contract the loop of metal lapped about the tube. This contracting tendency maintains good mechanical and thermal contact between the plate and the tube.

The tube thus serves as a mandrel about which the plate is swaged or deformed, and the deformation of the tube with the resulting radial expansion of confined portions thereof produces positive and permanent peripheral contact between the tube and the inner wall of the main groove 33 and of the deformed plate folds 48. This expansion of the tube accommodates any slight irregularities or distortions of either the plate or the tube so that virtually perfect, continuous metallic contact is obtained therebetween.

As a result of the deformation of both the tube and the plate, the members are in extended surface engagement over a tube area greater than its semi-periphery. If desired, the deformation of either the plate or the tube, or both the plate and the tube, into interlocking engagement may be either coextensive with the length of the plate 31 or for spaced distances along the length of the plate. The deformation of the tube obviates the difficulties heretofore caused by the attempted deformation of a plate into extended plate engagement with a tube of relatively large external diameter where the thickness was disproportionately thin.

The heat exchanger, as shown in Figure 5, thus includes the backing plate 31 and the continuous, sinuous tube 32, the straight portions of which are secured within the surface in grooves formed in the backing plate 31 by deformation of the backing plate into greater than semi-peripheral contact with the tubing and the deformation of the tubing radially outwardly into interlocking contact with the plate. The convex portions of the main grooves 33 and of the supplemental grooves 43 and 44 lie on the same side of the plate 31. Therefore, since the deformed portions 48 of the plate terminate approximately in the mean plane of the plate 31, a finished heat exchanger construction is provided having one substantially plane surface, as is desirable in many installations.

In practicing the method of Figures 1 to 4, it has been found that there is a definite ratio of plate thickness to tube diameter which is required if the plate is to exert a contractive force on the tube after the forming pressures have been moved. A one-quarter inch O.D. steel tube having a wall thickness of .028 to .031 inch will maintain a visually perfect roundness after assembly if

5 a plate of low carbon steel of about .0299 inch thickness is formed around the tube. The proportions have been found to be ideal for almost perfect end results mechanically and economically, and provide the desired inward contracting force of the plate on the tube without any need for deforming the tube. Heavier gages of tube and plate produce equally good mechanical results without the need for deforming the tube if the above ratio of plate thickness to tube thickness is maintained. For example, a one inch O.D. tube with .120 to .125 inch wall thickness and a plate of the same thickness produce an almost perfect product without the need for tube distortion. With these dimensions a two inch length of tube is clinched so tightly by a corresponding section of plate 10 that a free end of the tube cannot be manually rotated out of its original position relative to the plate.

15 It has been found that if the plate thickness is reduced to .014 inch and a one-quarter inch O.D. tube is employed having a thickness of about .028 inch, the quality as to the roundness of the tube and the plate surrounding the tube is substantially as good as with a plate thickness of .030 inch; however, the loop of plate surrounding the tube fails to exert an inward contractive pressure on the tube.

20 Figure 9 illustrates a test which was performed wherein successive sections of a single groove heat exchanger construction (made by the method of Figures 11, 12 and 13) were removed by means of a surface grinder with a $\frac{1}{16}$ inch rubber cut-off wheel. In the test, a 1 inch O.D. steel tube having a wall thickness of .125 inch and a plate 25 having a thickness of .0120 inch were utilized. Care was taken during the grinding operations to keep the specimen cool so that no thermal stresses would be set up. It was found that the residual stresses introduced in the plate 50 at the lower portion 50a thereof caused the plate to positively clinch the tubing. This fact was qualitatively demonstrated by the successive dissections which are represented by the section lines 1—1, 2—2, 3—3 and 4—4 in Figure 9. It was found that even after all 30 of the plate located above the center line 4—4 of the tube had been removed, the remaining portion 50a of the plate still pinched the tubing to such an extent that it was substantially impossible to separate the tube from this portion of the plate by hand.

35 Referring to Figure 10, the curve 51 represents the strain as measured with the post-yield strain gauge (indicated at 52 in Figure 10) located on the outside surface of the plate at the bottom portion 50a thereof as a function of load applied during formation of the tube and plate assembly indicated in Figure 9. The curve 40 indicates that the material yields in compression (as indicated at 51a) before any buckling of the sides of the plate takes place. In this first stage of the clinching process the material follows the conventional stress-strain curve for ductile materials. However, as the sides of 45 the plate groove buckle and begin to fold in, it is apparent that the load on the lower section of the plate becomes tensile. Thus, at a load of approximately 30,000 pounds, the curve actually reverses itself and as indicated at 51b, the tensile loading on the lower portion 50a of the plate shows up as a relief of the compressive strains present. As soon as the metal is formed completely around the tubing any continued loading results in further compressive yielding as indicated by the portion 51c of the curve.

50 It should be noted that the data for the curve of Figure 10 was obtained during the formation of a heat exchanger assembly by the method of Figures 11, 12 and 13, using a single tube length. During fabrication with a plurality of lengths of tubing as in Figures 1 to 4, the material of each land between adjacent grooves in the plate is restrained from movement toward either groove, and there is a tendency to stretch the part of the plate being wrapped about each length of tubing. Thus there would be a considerably higher tensile loading on the lower part of the plate below the horizontal

diameter of the tubing when a plurality of tube lengths are secured to the plate, and undoubtedly this would cause a greatly increased dip in the curve at 51b where reversal of strain takes place.

Figures 11, 12 and 13 represent diagrammatically the condition of the plate at stages in the forming operation represented by portions 51a, 51b and 51c of curve 51 in Figure 10 respectively. The plate is preferably preformed with its lateral edges 53 offset downwardly for the same reasons discussed in connection with edge 11a in Figure 2.

Referring now to Figures 14 to 19 of the drawings, a method of forming a tube and wire heat exchanger is illustrated. In this method, a straight length of wire such as indicated at 60 is first provided with a plurality of grooves or bends 61, which grooves extend transversely to the length of the wire and have semi-circular portions 61a defining the bottoms of the grooves of substantially the same inside diameter as the outside diameter of the tubing 62 to be inserted therein. The grooves also include generally straight upstanding parallel portions of the wire 61b defining the sides of the groove and rising above the tubing when the tubing is bottomed in the grooves. The ends of the wire may be offset as indicated at 61f as disclosed in connection with the offset 11a in Figure 2.

During the forming operation as illustrated in Figure 15, the semi-circular portions 61a of the wire are rigidly and conformingly backed by means of a lower die 64. The lower die 64 as indicated in Figure 19 is provided with a transverse groove 65 having a semi-cylindrical bottom portion 65a of diameter to exactly receive the external diameter of the tubing. The die further has recessed portions spaced therealong as indicated at 65b for receiving the groove portions of successive wires, the spacing of the wires along each tube being indicated in Figure 18. The upper die 66 is provided with protuberances such as 67 for exerting a reshaping pressure against unbacked upstanding portions 61b of each groove and contiguous portions 61d of the wire on each side of the groove to form a fold. The folds on each side of the groove are moved toward each other and reshaped into conforming contact with the tubing.

A punch bar 68 carried with the upper die 66 deforms the tubing 62 into a non-circular cross section including a flat portion 62a. This flattening operation also drives portions of the tube 62 against the adjacent portions of the wires to wrap the tube partially about the wires as indicated at 69 in Figure 18. The protuberances 67 simultaneously drive the portions 61c of the wires against the portion 69 of the tubing. Thus the wire is actually indented into the tube to form a series of transverse ridges such as 70 in Figure 18 which will cause turbulence in the flow of heat exchange fluid through the tubing.

The dies may also be so proportioned as to flatten the wires at 61e between the successive lengths of tubing in order to increase the radiating area.

According to a further feature of the present invention, instead of separate straight lengths of wire such as 60 in Figure 14, the method of this embodiment may be practiced on a sinuous wire 60' as shown in Figure 20. Since 120 or more wire lengths may be utilized per assembly, it will be appreciated that the use of a sinuous wire, cut off to the desired length, will effect great simplification in the method of this embodiment. In practicing the method on the sinuous wire 60', it will be understood that spaced grooves or bends are formed in each straight length portion such as 60" of the wire. It will be understood that each groove of each straight length such as 60" will be in longitudinal alignment with corresponding grooves in each of the other straight lengths of the wire to give a resultant structure as shown in Figure 18. The method practiced on the sinuous wire

of Figure 20 is thus identical to that disclosed in Figures 15 to 19.

The assembly may be finished by hot galvanizing, or a black enamel paint finish may be applied. If desired, the assembly may be welded in several places to increase its rigidity without unduly sacrificing the manufacturing advantages of the present invention.

The term "groove" as used in the claims is intended to be descriptive of both an elongated U-shaped bend in a plate and a U-shaped bend in a wire.

The plate or wire is considered as being "backed" in the description and claims if movement is substantially restrained at some time during the forming operation whether or not the plate or wire is initially supported by a stationary die surface, for example, and is considered as being operatively or effectively "unbacked" if no such restraint is applied during the forming operation.

It will be apparent that modifications and variations may be effected without departing from the scope of the novel concepts of the present invention.

I claim as my invention:

1. A tube and plate assembly comprising a generally flat sheet metal backing plate having a plurality of main grooves and a parallel contiguous shallower auxiliary groove on each side of each of said main grooves and extending continuously for the entire length of the main grooves, all of said grooves being concave in cross-section and offset from and lying on the same side of the general plane of said backing plate, and a length of metal tube in each of said main grooves, there being an acute angle fold of metal integral with said plate metal formed at the junction between closely spaced oppositely concave portions of each main groove and each of the corresponding auxiliary grooves, an opposed pair of such metal folds overlying the tube in the main groove and holding the wall of said main groove in greater than semi-peripheral conforming surface contact with said tube.

2. A tube and plate assembly comprising a generally flat sheet metal backing plate having a plurality of main grooves and a parallel contiguous shallower auxiliary groove on each side of each of said main grooves, all of said grooves being concave in cross-section and offset from and lying on the same side of the general plane of said backing plate, a length of metal tube in each of said main grooves, there being an acute angle fold of metal integral with said plate metal formed at the junction between closely spaced oppositely concave portions of each main groove and each of the corresponding auxiliary grooves, an opposed pair of such metal folds overlying the tube in the main groove and holding the wall of said metal groove in greater than semi-peripheral conforming surface contact with said tube, the exposed portion of said tube between said folds being non-circular and holding remaining portions of said tube engaged by the plate in tight metal-to-metal peripheral surface engagement with the inner wall of said groove.
